ATTORNEY.

UNITED STATES PATENT OFFICE

AARON KLOTZMAN, OF BALTIMORE, MARYLAND, ASSIGNOR TO MAY OIL BURNER CORPORATION, A CORPORATION OF MARYLAND

ATOMIZER

Application filed January 23, 1932. Serial No. 588,461.

This invention relates to atomizers and has particular reference to nozzles employed in oil-burners for atomizing fuel oil and ejecting the same into a furnace or other 5 combustion device.

Among the objects of this invention is the provision of an atomizer with a whirling chamber of substantially permanent dimensions for promoting stability in quantity and 10 physical characteristics of the dispersed liquid issuing from the atomizer.

A more specific object of this invention is the provision in the distributor of an atomizer of a jewel at the distributing end for 15 making this part of the device effectively resistant to corrosion and wear by the oil.

Other, further and more specific objects of this invention will become readily apparent to persons skilled in the art from a consideration of the following description when taken in conjunction with the accompanying drawing wherein;

Fig. 1 is an enlarged elevation, partly in section, showing the body, head and distributor of an atomizer, a flat top jewel being set in the distributor pin and a jewel in the tip 25 of the head.

Fig. 2 is an enlarged top plan view of the distributor pin, showing the tangential ducts 30 for the flow of the oil from the body of the atomizer to the whirling chamber.

Fig. 3 is an enlarged fragmental view, illustrating the use of a jewel with a top cavity in the distributor pin and a jewel in the 35 tip of the head.

Fig. 4 is a view similar to Fig. 3 and illustrates the use of a jewel in the distributor pin, but no jewel in the tip of the head.

Fig. 5 is another enlarged fragmental view 40 in section, illustrating the use of a flat top jewel in the distributor and a jewel with a whirling chamber in the tip of the head and ducts formed by one of the jewels and slots in the adjacent portion of the other jewel 45 for delivering oil into the whirling chamber.

Fig. 6 is a view similar to Fig. 5, but with the oil ducts entirely within the jewel setting in the tip of the head.

The apparatus comprises the body 1 of 50 hollow cylindrical construction connected at

one end 2, to an oil supply pipe (not shown) and at the other end 3 to the head 4. This head has at its tip 5 a jewel 6 securely set therein. This jewel 6 is preferably a natural sapphire, but other jewels such as ruby, diamond, or corundum may be employed. Also, the corresponding artificial jewels may be used, although as yet they have not been found as satisfactory as the natural ones. 55

The jewel 6 has extending therethrough 60 the small perforation 7 and the larger opening 8 continuous with the perforation 7.

The distributor pin 9 extends from the body 1 wherein it is preferably centered by a suitable disc 10 and is provided at its distributing 65 end with a jewel 11, preferably like jewel 6. The top of the jewel 11 is brought to the bottom of the opening 8 in the jewel 6. Oil passes through the body 1 from the oil supply, then around the space 12 between the head 4 70 and distributor pin 9 and then through the ducts 13 to the whirling chamber formed by the top of the jewel 11 and the opening 8 in the jewel 6. In the drawing, four ducts are shown, but any other suitable number may 75 be used. The ducts are preferably tangential and when oil under pressure issues through these ducts into the whirling chamber it will be given a whirling movement and will pass out through the orifice 7 in the form 80 of a spray. The disc 10 has perforations 10a to allow the oil to pass therethrough.

This form of atomizer possesses superior 85 advantages over those heretofore employed. With the jewels 6 and 11 forming the whirling chamber, there is assurance that such chamber will be permanent in size and shape and will be practically unaffected by the oil whirling therein. Also, by having the spray-ejecting orifice 7 in the jewel, the size of this 90 orifice will be permanent. This assures a steady flow of atomized oil from the atomizer with practically uniform physical properties as long as oil of the same kind, viscosity and pressure is delivered through the ducts 13. 95

In the modification shown in Fig. 3, the jewel 11 is formed at the top with a cavity 14, the wall of which is adjacent to and continuous with that of the opening 8 in the jewel 6. Here also the whirling chamber is defined by 100

the jewels 6 and 11 and consists of the opening 8 and cavity 14. By providing the cavity 14, the capacity of the atomizer is increased due to increase in size of the whirling chamber.

In the modification shown in Fig. 4, the distributor pin 9 is provided with a jewel 11 like that in Fig. 3, but there is no jewel in the tip of the head 4, the orifice and upper part 10 of the whirling chamber being formed directly in the tip. This modification is not as desirable as the others.

It will be seen by reference to Figs. 1, 3 and 4 that the distributor pin 9 is in the form of 15 a rod and rests in the disc 10. When in operative position, the top of the distributor pin and the jewel 11 bear against the head, the ducts 13 extending from the interior space 12 of the body 1 through the jewel 11 to the 20 whirling chamber.

In Figs. 5 and 6, the distributor is part of the top of the body 1 and in this top is set the jewel 11, which may have a flat top as shown in these views or a cavity to form part of the 25 whirling chamber similar to Figs. 1, 3 and 4. The top of the body 1 is also provided with passages 15 extending to an annular groove 16, whereby communication is established with the ducts 13 which lead to the whirling 30 chamber. These ducts 13 may be at the junction between the jewels 6 and 11 and in the form of a slot in one of the jewels with the other jewel serving as a wall for the duct, as shown in Fig. 5, where the slot is in the jewel 35 6. Also, the ducts 13 may be confined to one of the jewels, as shown in Fig. 6, where passages 17 of sufficient extent are provided in jewel 6 adapted to register with the annular groove 16 so as to afford communication be- 40 tween the ducts 13 and the interior of the body 1 irrespective of any displacements occasioned in the attachment of the head 4 to the body 1.

In the construction shown in Figs. 1, 3, 45 5 and 6, the oil both enters and leaves the whirling chamber through openings in jewels, thereby affording permanence in control of a kind very highly desired but not heretofore obtained in devices for atomization of 50 liquids.

The present invention is not limited to the specific details set forth in the foregoing examples which should be construed as illustrative and not by way of limitation, and 55 in view of the numerous modifications which may be affected therein without departing from the spirit and scope of this invention, it is desired that only such limitations be imposed as are indicated in the appended claims.

60 I claim as my invention:

1. In an oil burner atomizer, means for effecting permanency in quality and quantity of delivery of oil from the atomizer when oil is delivered to the atomizer at high pressure, 65 said means comprising a head with a spray-

ejection orifice, a whirling chamber and a distributor having at its distributing end a portion defining part of the said whirling chamber, said portion having secured therein a setting of a substance of the group comprising sapphire, ruby, corundum and diamond, and said atomizer having a whirl-producing duct for admitting oil into the whirling chamber.

70 2. In an oil burner atomizer, means for effecting permanency in quality and quantity of delivery of oil from the atomizer when oil is delivered to the atomizer at high pressure, said means comprising a head with a spray-ejection orifice, a whirling chamber and a distributor having at its distributing end a portion defining part of said whirling chamber, said portion having secured therein a sapphire setting, and said atomizer having a whirl-producing duct for admitting oil into the 75 whirling chamber.

80 3. In an oil burner atomizer, means for effecting permanency in quality and quantity of delivery of oil from the atomizer when oil is delivered to the atomizer at high pressure, said means comprising a head with a spray-ejection orifice, a whirling chamber and a distributor having at its distributing end a portion defining part of the said whirling chamber, said portion having secured therein a setting of a substance of the group comprising sapphire, ruby, corundum and diamond, and said atomizer having a whirl-producing duct passing through said substance 85 of the distributor for admitting oil into the 90 whirling chamber.

95 4. In an oil burner atomizer, means for effecting permanency in quality and quantity of delivery of oil from the atomizer when oil is delivered to the atomizer at high pressure, said means comprising a head with a spray-ejection orifice, a whirling chamber and a distributor having at its distributing end a portion defining part of said whirling chamber, said portion having secured therein a sapphire setting, and said atomizer having a whirl-producing duct passing through said sapphire for admitting oil into the 100 whirling chamber.

105 5. In an oil burner atomizer, means for effecting permanency in quality and quantity of delivery of oil from the atomizer when oil is delivered to the atomizer at high pressure, said means comprising a distributor and a head with a spray-ejection orifice, said distributor having at its distributing end a setting of a substance of the group comprising sapphire, ruby, corundum and diamond with a cavity in said setting at said distributing end forming a whirling chamber for the atomizer, and said atomizer having a whirl-producing duct for admitting oil into the 110 whirling chamber.

115 6. In an oil burner atomizer, means for effecting permanency in quality and quantity 120

- of delivery of oil from the atomizer when oil is delivered to the atomizer at high pressure, said means comprising a distributor and a head with a spray-ejection orifice, said distributor having at its distributing end a sapphire setting with a cavity in said setting at said distributing end forming a whirling chamber for the atomizer, and said atomizer having a whirl-producing duct 5 passing through said sapphire for admitting oil into the whirling chamber.
7. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having at its distributing end a substance of the group comprising sapphire, ruby, corundum and diamond, said enlarged opening in said head forming the whirling chamber of the atomizer and said orifice leading outwardly from said enlarged opening, and said atomizer having a whirl-producing duct 15 passing through said substance of the distributor for admitting oil into the whirling chamber.
8. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having a sapphire setting at its distributing end with 20 a cavity in said setting at said distributing end, said whirling chamber of the atomizer comprising the enlarged opening in the head and the cavity in the sapphire, said orifice leading outwardly from said enlarged opening, and said atomizer having a whirl-producing duct 25 passing through said sapphire for admitting oil into the whirling chamber.
9. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having 30 at its distributing end a setting of a substance of the group comprising sapphire, ruby, corundum and diamond with a cavity in said setting at said distributing end, said whirling chamber of the atomizer comprising the enlarged opening in the head and the cavity in said substance, said orifice leading outwardly from said enlarged opening, and said atomizer having a whirl-producing duct 35 passing through said substance in said distributor for admitting oil into the whirling chamber.
10. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having a sapphire setting at its distributing end with 40 a cavity in said setting at said distributing end, said whirling chamber of the atomizer comprising the enlarged opening in the head and the cavity in the sapphire, said orifice leading outwardly from said enlarged opening, and said atomizer having a whirl-producing duct passing through said sapphire for admitting oil into the whirling chamber.

whirl-producing duct passing through said sapphire for admitting oil into the whirling chamber.

9. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having 70 at its distributing end a setting of a substance of the group comprising sapphire, ruby, corundum and diamond with a cavity in said setting at said distributing end, said whirling chamber of the atomizer comprising the enlarged opening in the head and the cavity in said substance, said orifice leading outwardly from said enlarged opening, and said atomizer having a whirl-producing duct 75 passing through said substance in said distributor for admitting oil into the whirling chamber.
10. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having a sapphire setting at its distributing end with 80 a cavity in said setting at said distributing end, said whirling chamber of the atomizer comprising the enlarged opening in the head and the cavity in the sapphire, said orifice leading outwardly from said enlarged opening, and said atomizer having a whirl-producing duct 85 passing through said sapphire for admitting oil into the whirling chamber.
10. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having a sapphire setting at its distributing end with 90 a cavity in said setting at said distributing end, said whirling chamber of the atomizer comprising the enlarged opening in the head and the cavity in the sapphire, said orifice leading outwardly from said enlarged opening, and said atomizer having a whirl-producing duct 95 passing through said sapphire for admitting oil into the whirling chamber.
10. In an oil burner atomizer, means for effecting permanency in quality and quantity of delivery of oil from the atomizer when oil is delivered to the atomizer at high pressure, said means comprising a distributor and a head with a spray-ejection orifice and an enlarged opening, said distributor having a sapphire setting at its distributing end with 100 a cavity in said setting at said distributing end, said whirling chamber of the atomizer comprising the enlarged opening in the head and the cavity in the sapphire, said orifice leading outwardly from said enlarged opening, and said atomizer having a whirl-producing duct passing through said sapphire for admitting oil into the whirling chamber.
